UNITED STATES PATENT OFFICE.

HARRIETTE E. HODGSON, OF NEW YORK, N. Y.

ARTIFICIAL ARM.

Application filed August 22, 1923. Serial No. 658,765.

To all whom it may concern:

Be it known that I, HARRIETTE E. Hodgson, a citizen of the United States, and a resident of the city of New York, in the 5 county and State of New York, have invented a new and useful Artificial Arm, of which the following is a specification.

The object of the invention is to provide an artificial arm which shall be strong, durable, comfortable and inexpensive, which shall be useful for ordinary purposes, and with which the user can conveniently exert a large amount of power in doing work.

In the accompanying drawings forming 15 part hereof:

Fig. 1 is a perspective view showing the slit in the coat and shirt sleeves open, the artificial arm being indicated in different positions by dot and dash lines;

20 Fig. 2 is a side view of the artificial arm; Fig. 3 is a plan view;

Fig. 4 is a side view in its bent position;

25 Fig. 5 is an enlarged detail view of the upper end of the arm; and

Fig. 6 is an enlarged sectional view taken 30 on the line 6—6 of Fig. 2.

The arm comprises an upper arm section 1 and a forearm section 2, which are of rigid hollow construction, preferably of 35 cast metal. Aluminum may be employed, or another metal or alloy of proper strength and not too great weight. With the sections of the arm made of shells of this character great strength can be secured, 40 and the arm can be practically indestructible.

The proximate ends of the sections enter 45 one into the other, and are suitably cut away for bending movement. They are connected by a transverse pivot pin 3 which passes through the overlapped walls at the two sides and across the interior. The pin has a head 4 at one end and is screw-threaded adjacent the head and at its 50 other end to receive nuts 5, 6 and 7, the head and the nuts forming pairs of abutments at opposite sides of the pairs of walls, whereby a strong joint is produced. For further strength and solidity a spacer 8, 55 preferably, though not necessarily, in the form of a ball, is placed on the pin in the interior of the joint, between the nuts 5 and 6.

The top of the upper section 1 is formed 60 with slotted openings 9 to receive straps by

means of which the arm is attached to the person. Rows of smaller openings 10, 11 provide for sewing in the felt lining 12 and for ventilation.

The forearm section can be rigidly braced 60 to the upper arm section in various positions, by means the preferred form of which is about to be described.

A hasp hook 13 is pivotally supported on 65 an eye 14 on the upper arm section a short distance above the elbow joint, and on the inner side with respect to this joint, that is to say the side that is inside the angle when the joint is bent. On the inner side of the forearm section there is a longitudinal series 70 of eyes 15, so positioned as to be engaged selectively by the hook-end of the hook 13 when the arm is bent at various angles. The hook then forms a rigid brace enabling the arm to sustain a heavy weight or to transmit a substantial amount of power in operations calling for a bent arm, as well as enabling lighter things to be done.

The hook can be locked to any one of the 75 eyes 15 by a nut 16, which screws onto a 80 thread provided for the purpose on the end of the hook. The extent of the thread is such that when the nut is screwed up the eye 15 will be clamped between the nut and the back of the hook, so that looseness is 85 avoided.

When the hook 13 is not in use it is turned 90 upward and engaged with an upper eye 17 on the upper arm section, where it can also be secured by the nut 16. The nut is retained against loss by a chain 18, in one 95 end of which it is swiveled, the other end of the chain being secured to the eye 14 or other suitable point of attachment.

At opposite sides of the upper arm section, slightly above the joint, are eyes 19 to which are pivoted a pair of hooks 20. These hooks are positioned to engage eyes 21 on the forearm section, when the arm is straight or substantially so, for the purpose 100 of holding the arm rigidly in this position and bracing it against lateral stress. In this condition the hooks lie somewhat back of the elbow joint pivot 3. The hooks 20 when not in use are caught up on eyes 22, and when in engagement with either the eyes 21 or 22 they are secured by nuts 23 on chains 24.

The forearm section terminates in a screw 110 stem 25 to receive an artificial hand, such

as one of the artificial hand forms disclosed in my application Serial No. 653,865, filed July 26, 1923. A hook 26 swung on an eye 27 on the inner side of the wrist portion of the forearm section is provided for the purpose of engaging an eye on the hand, to keep it from unscrewing. A chained nut 28 is provided to cooperate with this hook, after the manner of the other hooks and nuts.

The hasp-hooks with nuts preferably employed herein as the means for rigidly bracing the forearm section to the upper arm section in various positions are the subject matter of a patent numbered 1,468,861, granted to me September 25, 1923.

In order to stay the artificial arm as a whole against stress acting laterally outward from the body, and to relieve the wearer's arm stump which is inserted in the upper section, a sling 29 may be fastened to the upper arm section, to be tied about the wearer's chest. A keeper 30 on the arm prevents such sling from slipping up or down.

It is advantageous to construct the joint between the arm sections so as to have a sufficient amount of friction to hold the forearm section in any desired position relative to the upper arm section irrespective of the hooks when work requiring effort is not to be performed with the arm.

It will be understood that the hook supports and fastenings on the upper arm section should be applied in such a way that the inner ends of those of them that may

be at the region occupied by the arm stump will afford no projection on the interior.

In order to afford means of access to the braces and fastenings constituted by the hooks, eyes and nuts, both the shirt sleeve *a* and the coat sleeve *b* must be slit along the inner side. The slit in the shirt-sleeve should be of considerable length for convenient operation. The slit in the coat sleeve can be closed by snaps *c*.

While the preferred embodiment of the invention and the best ways of using the same now known to me have thus been described, it will be understood that I do not wish to limit myself to the precise form and details.

What I claim as new is:

1. An artificial arm, comprising an upper arm section and a forearm section of rigid hollow construction, a joint connecting the sections, hook and eye devices on the sections for rigidly supporting the forearm section in various angular positions and other hook and eye devices on the sides of the sections for bracing them when straightened against lateral stresses.

2. An artificial arm, comprising an upper arm section, a forearm section, a joint connecting the sections, two hooks pivotally connected to one of the sections at opposite sides, and eyes upon opposite sides of the other section, whereby the sections can be held rigidly and stayed against lateral stresses.

HARRIETTE E. HODGSON.
